Des. 182,243
Patented Mar. 4, 1958

182,243

SNACK TRAY

Ronald J. McCaig, Chicago, Ill.

Application May 8, 1957, Serial No. 46,060

Term of patent 14 years

(Cl. D44—10)

FIG. 1

FIG. 2

FIG. 3

Figure 1 is a perspective view of a snack tray showing my new design, a tumbler and cigarette being shown in broken lines for purposes of illustration.

Fig. 2 is a top plan view.

Fig. 3 is a cross sectional view taken on the line 3—3 of Figure 2.

I claim:

The ornamental design for a snack tray, as shown and described.
